UNITED STATES PATENT OFFICE.

ALBERT W. NICHOLLS, OF CHICAGO, ILLINOIS, ASSIGNOR OF ONE-HALF
TO F. P. NOERA, OF WATERBURY, CONNECTICUT.

GAS-LAMP.

SPECIFICATION forming part of Letters Patent No. 781,784, dated February 7, 1905.

Application filed October 6, 1904. Serial No. 227,452.

To all whom it may concern:

Be it known that I, ALBERT W. NICHOLLS, a citizen of the United States, residing at Chicago, in the county of Cook and State of Illinois, have invented certain new and useful Improvements in Gas-Lamps; and I do declare the following to be a full, clear, and exact description of the invention, such as will enable others skilled in the art to which it appertains to make and use the same.

This invention relates to gas-lamps; and one of the objects of the same is to provide a stand-lamp for use with a mantle-burner and to provide means in such a lamp for reducing or absorbing the vibratory movements which are liable to injure or break the fragile mantle.

Another object is to provide improved fittings for this character of lamp; and still another object is to provide means for vertically guiding the burner-tube relatively to the stand or base.

These and other objects are attained by means of the construction illustrated in the accompanying drawings, in which—

Figure 1 is a central vertical section of a gas-lamp made in accordance with my invention. Fig. 2 is an elevation and partial section of a slightly-modified form of my invention, and showing the lamp connected by means of a flexible tube to a wall-bracket or burner. Fig. 3 is a vertical sectional view of a modified form of lamp provided with means for vertically adjusting the burner-tube and also provided with means for absorbing or counteracting the vibrations or jars of the lamp. Fig. 4 is a side elevation of a lamp of modified form. Fig. 5 is a side view and partial section of my improved stork-neck and fittings therefor.

Referring to the drawings for a more particular description of my invention, the numeral 1 denotes the base portion of the lamp, and, as shown in Fig. 1, this base is hollow and provided with an offset or enlargement 2 at its lower portion to provide means for holding a casting or metal weight 3, designed to afford a firm stand for the lamp and to prevent it from being easily tipped over or jarred. The weight 3 is recessed at 4 to accommodate

the flexible tubing 5. An interiorly-threaded fitting 6, provided with a tapering nipple 7, forms a connection for the flexible tubing 5, the nipple being passed through an aperture in the base and extended into the end of the tubing, a washer 8 being fitted to the enlarged portion of the nipple and bearing against the inner wall of the base. The upper end of the tube 5 is connected to a similar nipple 9, having an enlarged threaded portion 10, fitted within a connection 11, the burner-tube 12 being screwed into said connection and extending up and out of the stand and provided at its terminal end with a burner seat or cap 13.

A spiral spring 14 is seated at its lower end upon the connection 11, said spring extending up toward the top of the stand, where its upper end is connected to a fitting 15, having a reduced portion 16, which serves as a guide for the burner-tube in its vertical vibrations.

A metal tube 17 is connected at its lower end to a nut 18, bearing against a washer 19, seated in a recess near the upper end of the base 1, said tube 17 surrounding the burner-tube 12 and the spring 14 and extending up within the stand, where its upper end is connected to a cap 20, resting upon the fitting 15.

A cap 21, provided with a central opening to receive the reduced portion 16 of the fitting 15, has connected to its lower end the outer tube 22, the lower end of which is firmly seated in a recess 23, formed in the upper end of the base 1.

The burner-tube 12 near its upper end passes through a smoothly-bored portion of the fitting 15 and can have a slight vertical movement therein in case the lamp should be subjected to a jar sufficient to extend or contract the spring 14, the latter serving to cushion or relieve the shocks to which the mantle may be subjected.

Owing to the heavy base 1 and the spring 14 the slight vibrations to which mantle-lamps are subjected are to a great extent counteracted and absorbed.

In Fig. 2 the lamp is provided with a solid cast-metal base 24, provided with an opening for the flexible tubing 25, the inner end of

which is connected in a manner similar to that shown in Fig. 1 to a nipple and fitting 26. A heavy spiral spring 27 surrounds the vertical portion of the stand, its lower end being secured to the base and its upper end to a cap 28. The burner-tube in this structure is also capable of adjustment in a manner similar to that of Fig. 1, and the antivibratory features are also retained in this construction. The flexible tubing 25 comprises an inner rubber tube 29, a surrounding spring 30, and braided jackets 31 32, united to the inner rubber tube 29 and the spring 30 by an adhesive gas-proof compound 33, containing glue and glycerin. The smooth rubber inner tube 29 affords a better conductor for the gas than tubes having inner spring or corrugated linings, and I am enabled to get a more powerful light owing to increased gas-pressure afforded by the smooth inner surface of the tube.

As shown in Fig. 3, the outer spring 34 is enlarged at its central portion, and the burner-tube is held in vertical adjustment by means of the thumb-screw 35, which passes through a bearing or boss 36, connected to the cap 35 by a threaded projection 37.

In the construction shown in Fig. 4 the inner tube 17 is omitted and the outer spring 38 is not enlarged centrally, as is the case in Fig. 3.

As shown in Figs. 2 and 5, a stork-neck 38 is fitted to the upper end of the tubing 25 and a ground-joint fitting is provided for connection to the gas-supply nipple. In Fig. 2 the ground-joint connection comprises a flaring tube 39, fitted upon the end of the stork-neck 38 and having a flange 40 at its lower end. Fitted within the tube 39 is a tapering connection 41, the outer surface of which is ground to fit the ground inner surface of the tube 39, and said two parts being firmly united by means of a threaded ring 42, having a flange 43 to engage the flange 40 and a threaded engagement with the enlarged lower end of the connection 41, as will be understood upon reference to the drawings.

The construction shown in Fig. 5 is slightly modified. The stork-neck 38 is fitted to a

tapering tube 44, having an outer ground surface fitted within an oppositely-tapered tube 45, which has its inner wall ground to fit the tube 44. A threaded ring 42 serves to tighten the joint in an obvious manner.

From the foregoing it will be seen that my invention provides a gas-lamp of comparatively simple construction, comprising means for counteracting vibrations or jars, means for adjusting the burner-tube vertically, and having other features of construction, which render the lamp strong, durable, efficient, and comparatively inexpensive to manufacture.

Various changes in the shape, proportions, and minor details of construction may be resorted to without departing from the principle of or sacrificing any of the advantages of this invention.

Having thus described my invention, what I claim as new, and desire to secure by Letters Patent, is—

1. A gas stand-lamp comprising a weighted base, a spiral spring connected at one end to the base and rising therefrom, a burner-tube within the spring, a flexible tube extending into the base and connected to the burner-tube, a fitting connected to the upper end of the spiral spring, the burner-tube passing through said fitting, and guided thereby in its vertical vibrations, substantially as described.

2. A gas stand-lamp consisting of a hollow base having a weight therein, a tube connected to said base and extended upward therefrom, a spiral spring within said tube, a burner-tube within said spiral spring, and connected thereto at its lower end, a flexible tube extending into the base and connected to the lower end of the burner-tube, and a fitting through which the burner-tube is guided in its vertical vibrations, substantially as described.

In testimony whereof I have hereunto set my hand in presence of two subscribing witnesses.

ALBERT W. NICHOLLS.
